DESIGN FOR A DISPLAY CONTAINER

Albert T. Tobey, Binghamton, N. Y., assignor to Spaulding Bakeries, Inc.

Application December 29, 1938, Serial No. 32,038

Term of patent 14 years

To all whom it may concern:

Be it known that I, Albert T. Tobey, a citizen of the United States of America, residing at Binghamton, in the county of Broome and State of New York, have invented a new, original, and ornamental Design for a Display Container, of which the following is a specification, reference being had to the accompanying drawing, forming a part thereof, wherein:

The drawing is shaded to indicate contrasting colors.

I claim:

The ornamental design for a display container, substantially as shown and described.

ALBERT T. TOBEY.
